REFINING PROCESS CORPORATION, OF LOS ANGELES, CALIFORNIA, A CORPORA-
TION OF NEVADA.

OIL-CRACKING PROCESS AND APPARATUS.

Application filed August 27, 1925. Serial No. 52,749.

This invention has to do with process and apparatus for cracking hydro-carbon oils, and without the purposes of the invention being limited thereto, its chief object may be stated to include the provision of oil cracking apparatus and a process or method of cracking therein whereby the apparatus will continuously function, without interruptions, to produce a high quality of low boiling point hydro-carbons, and without the production of any large proportion of fixed gases.

Several different processes of cracking hydro-carbons to low boiling point hydro-carbons have been previously known in the art; but one of their outstanding short-comings has been the production of carbonaceous deposits in such large quantity or in such physical form as to make difficult the discharge of such deposits from the cracking still, usually necessitating temporary shutdown of the still for cleaning. It is one of the objects of this invention to provide such form of apparatus and process as to give a comparatively finely divided and dry carbonaceous deposit, and to provide easy means for removal of the deposit while the still is continually operated.

How these and other objects are accomplished will be best understood from the following detailed description of preferred forms of apparatus and of the process carried on in such apparatus, reference for that purpose being had to the accompanying drawings, in which:

Fig. 1 is a vertical longitudinal section showing one form of my still and its accompanying apparatus;

Fig. 2 is a somewhat enlarged vertical longitudinal section of the still itself.

Fig. 3 is a vertical longitudinal section of another form of still and its accompanying furnace.

Fig. 4 is an enlarged longitudinal section of the still of Fig. 3; and

Fig. 5 is a diagram in the nature of a flow-sheet illustrating the complete apparatus for carrying out my process.

I refer first to Fig. 5 in order to give a general description of the process as a whole.

It will be noted that the original hydro-carbon oil is fed through pipe 10 to a heat exchange 11, the relationship of which to the cracking still will be hereinafter explained. From this heat exchange the warmed oils 55 pass through pipe 12 to a low pressure pump 13, by which they are pumped through pipe 13^a through heater 14 under a pressure substantially just enough to cause them to flow at sufficient speed. Such a heater as illustrated at 14 is usually composed of a number of tubes connected at least partly in parallel relation so that the resistance to flow through the heater is comparatively small; and the oil having been preliminarily warmed in 65 heat exchange 11 no great pressure is necessary to flow the oil through heater 14. From heater 14 the heated oil goes through pipe 15 to a high pressure pump 16 and thence through pipe 17 to the cracking still 70 18. The gases and vapors generated in the cracking still pass out of it through vapor outlet pipe 19 to the heat exchange 11, first spoken of, where the vapors and gases give up a part of their heat to the original oils. 75 From the heat exchange the vapors and gases flow through pipe 20 to a condenser 21 whence the condensate is taken off at 22 and the separated gas goes to a gas container 23. This gas, or any other suitable fuel, may be 80 used at the burner 24 for firing the furnace of the cracking still.

In the form of cracking still shown in Figs. 1 and 2 the still proper is composed of a vertically arranged cylindrical shell 25, 85 standing in a furnace chamber 26, which is provided with a partition wall 27 of some suitable heat resistant material, of which the furnace walls are also composed. This central partition 27 forces the heated products 90 of combustion from combustion chamber 28 to pass first downwardly in contact with one-half, or substantially one-half, of the cylindrical still, then to pass under the lower end of the partition and upwardly in direct 95 contact with the other part of the cylindrical still. The gases of combustion pass out finally through opening 29 and pass directly into the heater 14, and thence out of the apparatus through stack 30. Heater 14 may 100

be a heat exchange of a well-known type, embodying a plurality of cross tubes 31, through which the oil flows.

The furnace structure in which still 18 is set has an offset combustion chamber 28, into which burner 24 throws its fuel either in admixture with air, or air is admitted in any ordinary way. Combustion taking place in chamber 28, the products of combustion pass 10 through the brick checker-work 35, wherein by intimate intermingling any unburned fuel is burned and all the products of combustion are made uniform in temperature. The heated products of combustion that then 15 pass over wall 36 into the furnace chamber 26 are as nearly uniform in temperature as may be. These provisions make it possible to heat the cracking still uniformly to a high temperature without any danger of burning 20 or otherwise deteriorating the still either by too high heating in spots or by being subjected to oxidizing or reducing gases at too high a temperature. The high temperature thus maintained uniformly in the still is one 25 of the things that enables me to obtain the uniform and efficient cracking action within it. However, when I refer to uniform temperatures within the still, I do not mean that the interior of the still, as a whole, is at the 30 same temperature throughout; but that there are no irregularities of temperature between different places in the still. As a matter of fact, the upper end of that side of the still, shown at the right hand in Fig. 1, 35 will usually be somewhat hotter than the opposite side of the still, although there may not be much difference in temperature. This difference in temperature may be due to the fact that the hot gases of combustion 40 come first into contact with the right hand side of the still and that the incoming oils are injected into the left hand side of the still. Thus the incoming oils in passing from the left hand to the right hand side of 45 the still, as will be hereinafter explained, may pass into zones of somewhat increasing temperature; but the temperature maintained at the point of injection of the oils is 50 always high enough to accomplish the operations hereinafter described.

The cylindrical still also has in its interior a partition wall 40 extending from its upper end to a point near its lower end, and there 55 it is preferably formed in such a manner as to leave a relatively restricted opening 41 between its lower end and the wall of the still for vapors and gases to pass into the space at the right of wall 40. In the form shown in Fig. 2 this interior partition 40 is spaced 60 so as to make a larger chamber at its left than at its right; but this is not necessarily the case. At the upper end of the right hand chamber of the still the vapor and gas outlet pipe 19 leads off; while the oil pressure pipe 17 leads to a small orifice nozzle 65

42 discharging downwardly into the left hand compartment of the still and discharging directly downwardly upon a cone-shaped spreader 43, supported upon a suitable spider or similar support 44.

The lower end of the still is cone-shaped, as shown at 45, and has a carbon outlet at 46 leading to two valve controlled pipes 47, which in turn lead to two carbon pots or receptacles 48, which have valve-controlled 75 outlets at 49. It is, of course, obvious how either one of the valves at 47^a may be opened while the other is closed, so that the carbonaceous deposits may be drained into one carbon pot, while the other is being drained 80 through its drain valve 49.

In applying my process to an average hydro-carbon oil or petroleum derivative of whatever nature, I find that it is advantageous to heat the oils in heater 14 to about 85 500° or 600° F., while they are still under low pressure—a pressure that may be called substantially atmospheric. Such temperature of heating varies with the oil being treated, but in any case it is preferably a 90 temperature that is as near as may be, in practical operation, to cracking temperature, but still not sufficient to crack the oils. Having thus been heated to this relatively 95 high but non-cracking temperature, the oils are then taken by high-pressure pump 16 and put under a pressure of from 600 to 700 pounds per square inch, so that the oil delivered to spray nozzle 42 is at a high pressure and also at the high temperature stated. 100 The still and its furnace are operated so as to maintain the still uniformly at a temperature of approximately 780° F., or more, the exact temperature depending upon that required to produce the particular desired result from the particular oils being cracked; and that temperature of the still is so maintained, and the flow of hydro-carbons into the still is so regulated that the difference in 105 temperature between the point where the oil is first introduced and the point where the vapor emerges is comparatively small—a difference of a few degrees. The oils upon being introduced through the small orifice nozzle 42 under the high pressure maintained by high pressure pump 16 are sprayed and atomized into a very fine mist; so that they almost instantaneously come into very finely divided and intimate contact with the body 110 of vapors in the still, which vapors are maintained at the temperature stated. The result of this intimate and practically instantaneous subjection to a higher and cracking temperature, and the simultaneous release of 115 pressure upon the oils, causes an almost instantaneous cracking transformation and causes a carbonaceous deposit to be dropped out of the oils in finely divided and comparatively dry particles. This finely divided carbon drops to the bottom of the still where 120

125

130

it easily passes out into one or the other of the carbon pots. After the practically instantaneous cracking action that takes place upon introduction of the oil, the resultant vapors are, of course, further subjected to the temperature and pressure conditions within the still during the time that they flow down through the left hand compartment of the still and up through its right hand compartment to the outlet pipe 19. The valve 19^a on this outlet pipe may be a valve of any suitable type, operated in any suitable manner, and it is regulated so as to maintain constantly within the still a pressure of from 150 to 200 pounds per square inch—a comparatively low pressure as cracking operations go. Maintaining thus a given pressure within the still, the time element involved in cracking operations within the still depends upon the quantity of oil put through the still in unit time; and this may be regulated by regulation of the high pressure pump and other parts of the circulating apparatus, and corresponding regulation of the outlet valve on the still to maintain the desired pressure. The vapors during their heat and pressure treatment in passing through the still may be subjected to further reactions; but the major cracking

action takes place practically instantaneously upon introduction of the oils to the still.

In the form of still apparatus shown in Figs. 3 and 4, the still proper 18^a is arranged horizontally; and in order to carry the carbonaceous deposit to the end of the still, away from the oil injection end, I provide a spiral scraper 50 mounted upon a shaft 51 (a spring spiral mounted at its ends on the shaft and expanding into contact with the still wall) and rotating to carry the carbonaceous deposit to the outlet 46^a. The oil pressure pipe 17 leads to the small orifice nozzle 42 at one end of the still, and the cone-shaped spreader 43 may be carried by the end of shaft 51. The vapor outlet is at 19^b. It will be seen that in either form of still the oils are injected at one end, the carbonaceous deposit is taken out at the lower part of the still at a distance from the point of injection, and the vapors are taken out of the upper part of the still at a distance from the point of injection.

For the horizontal still, the furnace arrangement is modified merely to suit the position of the still, the offset combustion chamber 28 and brick checker-work 35 being used, and the furnace chamber immediately surrounding the still being divided longitudinally of the still into two compartments by the longitudinal partition 27, as before explained.

It will be apparent to those skilled in the art that various modifications of operating conditions will have to be made in carrying out my process upon differing types of oils;

and, therefore, I wish it distinctly understood that the temperatures and pressures here given are indicative only and not necessarily specifically limitative. Likewise various modifications in the apparatus will suggest themselves to those skilled in the art and I, therefore, do not limit my invention except as expressly so limited in the following claims.

I claim:

1. The process of cracking high boiling point hydro-carbons to lower boiling point hydro-carbons, that includes heating the hydro-carbons to a temperature of about 500° to 600° F., under a low pressure, then placing the heated hydro-carbons under a pressure of about 600 to 700 pounds per square inch, delivering the hydro-carbons at that pressure to a still in which the pressure is maintained at about 150 to 200 pounds per square inch and in which a temperature of about 780° F., or more is maintained, atomizing the hydro-carbons at their point of delivery and pressure release into the still, and taking off from the still the resultant carbonaceous deposit and the vapors and gases evolved.

2. Hydro-carbon cracking apparatus, comprising an expansion cracking chamber, means for heating hydro-carbons and injecting them under high pressure to the expansion chamber, the injecting means including an atomizing nozzle with a small orifice through which the hydro-carbons are forced under high pressure into the expansion chamber, means to maintain the chamber at cracking temperature, means to maintain in the chamber a pressure substantially lower than that under which the hydro-carbons are forced into the chamber, a longitudinal partition extending within the chamber from one end to a point near the other, the hydro-carbon injecting nozzle being at one side of the partition at the first mentioned end, a valve controlled gas and vapor outlet at that same end at the other side of the partition, and a carbon outlet at the other end of the chamber.

3. Hydro-carbon cracking apparatus, comprising an expansion cracking chamber, means for heating hydro-carbons and injecting them under high pressure to the expansion chamber, the injecting means including an atomizing nozzle with a small orifice through which the hydro-carbons are forced under high pressure into the expansion chamber, means to maintain the chamber at cracking temperature, means to maintain in the chamber a pressure substantially lower than that under which the hydro-carbons are forced into the chamber, a longitudinal partition extending within the chamber from one end to a point near the other, the hydro-carbon injecting nozzle being at one side of the partition at the first

mentioned end, a valve controlled gas and vapor outlet at that same end at the other side of the partition, and a carbon outlet at the other end of the chamber, a furnace enclosing the chamber, a combustion chamber communicating with the furnace, and means for burning fuel in the combustion chamber, the furnace being arranged so that the products of combustion are conducted first into direct contact with that half of the ¹⁰ expansion chamber that is at the outlet side of the partition therein, and then into direct contact with the other half of the expansion chamber.

In witness that I claim the foregoing I ¹⁵ have hereunto subscribed my name this 21st day of August 1925

WILLIAM C. KIRKPATRICK.
